ABSTRACT: My invention comprises a novel cooperating yoke and rivet assembly for positively retaining right-angularly disposed concrete form sheets in such assembly for the reception of wet concrete mix for integrally forming walls of a building structure.

PATENTED OCT 5 1971

3,610,565

FIG. 1

FIG. 2

FIG. 3

FIG. 4

MIYONI OKAZAKI
INVENTOR.

BY *Miyon Okazaki*

ATTORNEYS

RETAINING MEMBER FOR RETAINING CONCRETE FORM SHEETS IN RIGHT-ANGULAR ASSEMBLY

In accordance with conventional practice, the provision of metallic forms for molding integral right-angularly disposed building walls such as sidewalls, or sidewalls and a ceiling, entails relatively costly devices which are difficult and time consuming to assemble and disassemble. It is also a well-known shortcoming of such forms that the right-angularly disposed form sheets tend to separate or move out of true right-angular relationship under the stresses imposed by the pouring and setting of the concrete mix.

It is a principal object of my invention to provide, for a concrete form, a novel yoke and rivet assembly which is readily adaptable to being employed to retain the form sheets in true right-angular relationship against the stresses imposed by the pouring and setting of the concrete mix.

It is also an object of my invention to provide economical means for retaining form sheets in true right-angular relationship which may be installed and taken apart with a minimum amount of labor.

It is a further object to provide novel means for preventing the contiguous edges of juxtaposed form sheets from separating.

For the purpose of further explaining my invention, I shall now describe presently preferred embodiments thereof by reference to the accompanying drawing wherein:

FIG. 1 is an elevational view, partly in section, showing one of my concrete form sheet retaining assemblies attached to a form;

FIG. 2 is a section taken on line 2—2 of FIG. 1;

FIG. 3 is a view similar to FIG. 1 but showing a variational form of the assembly; and

FIG. 4 is a side elevational view of a rivet employed in my assembly.

Referring now to the drawing (FIG. 1), the numeral 5 designates a conventional metallic form sheet for molding the inner or exposed surface of the ceiling of a building structure; and the numeral 6 designates a conventional form sheet for molding the inner surface of a sidewall of the building structure. It will be understood, of course, that, conventionally, there are outer form sheets (not shown) mounted in spaced-parallel relationship to the inner sheets whereby to provide therebetween a conventional chamber for receiving the wet concrete mix in the construction of the building.

My novel yoke member comprises a metal yoke having right-angularly disposed legs 10 and 11. Leg 11 has a longitudinal, tapered slot 14 to receive and pass the shank portion 15a of a rivet 15 (FIG. 3) whose inner end portion 15b is larger in diameter than the portion 15a of the rivet.

A rectangular metallic retaining strip 20 has its end portions disposed to be secured to the inner surface of the form sheet 6 as by riveting or welding, it being here shown as riveted. Intermediate its ends, the retaining strip is outwardly bent to provide a passageway for the leg 11 of the yoke.

The rivet 15 has an enlarged diameter headed portion 15b at its inner end; a portion 15a between its ends, of relatively

smaller diameter, preferably of a diameter equal to the thickness of the yoke leg 11; and has a relatively smaller diameter outer end portion 15c adapted to be inserted through a rivet hole (not shown) in the sheet 6 and adapted to be headed at its outer end to prevent the rivet from escaping from the rivet hole.

Ordinarily, before the form sheets are assembled, the portion 10 of the yoke is secured to the inner surface of the form sheet 5 and the retaining strip 20 is secured only at its end portions to the form sheet 6, and the rivet 15 is mounted on the form sheet 6 in the appropriate position in relation to the slot 14. Thus the form may be readily and quickly assembled and secured in assembly by inserting the yoke leg 11 through the passageway provided by the retaining strip 20. Of course, any desired number of the yoke assemblies may be employed, the purpose being to employ enough yoke assemblies positively to retain the form sheets 5 and 6 firmly assembled in true right-angular relationship.

In the embodiment of FIG. 2, the parts are the same except that there are two juxtaposed wall-molding sheets 6 and 7 which must be retained against spreading apart during the pouring and setting of the concrete mix; and the leg 11 of the yoke is relatively wide and has two laterally spaced slots 14a, 14b, those slots being so positioned that there will be one slot 25 in the portion of the yoke leg 11 which engages the form sheet 6 and one slot in the portion of the yoke leg which engages the juxtaposed form sheet 7.

I claim:

1. In a form sheet assembly having a first and second form sheet for integrally molding right-angularly disposed concrete wall portions of a building structure:

a. a rectangular metallic strip affixed to the first of said form sheets only at its end portions, said strip being outwardly bent intermediate its end portions so as to form a passageway therebetween;

b. a rivet anchored at its outer end to said first form sheet projecting inwardly therefrom, said rivet having a shank portion and an enlarged headed portion at its inner end; and

c. a yoke member adapted to cooperate with said metallic strip and said rivet comprising:

1. a first leg portion affixed to said second form sheet; and

2. a second leg portion disposed at right angles to said first leg portion, said second leg portion having a thickness substantially equal to the shank portion of said rivet, having a tapered slot adapted to pass over the shank portion of said rivet and being so constructed and arranged as to be slidably receivable within the passageway of said rectangular metallic strip when said strip is in position.

2. The device of claim 1 wherein the first of said sheets is comprised of separate juxtaposed sheet portions each presenting one of said rivets; and wherein said second leg portion of said first-mentioned yoke member has two laterally spaced, longitudinally disposed slots positioned to slidably receive said respective rivets.
